[57] CLAIM

The ornamental design for a vehicle wheel, substantially as shown and described.

DESCRIPTION

FIG. 1 is a right front perspective view of a vehicle wheel showing my new design.
FIG. 2 is a front elevational view thereof.
FIG. 3 is an enlarged sectional view taken along line 3—3 in FIG. 2.
FIG. 4 is an enlarged sectional view taken along line 4—4 in FIG. 2.
FIG. 5 is an enlarged sectional view taken along line 5—5 in FIG. 2.
FIG. 6 is a left front perspective view of a vehicle wheel showing a second embodiment of my new design.
FIG. 7 is an enlarged sectional view taken along line 7—7 in FIG. 6.

—FIG. 1

—FIG. 2

FIG. 3

FIG. 4

— FIG. 5
